OHIO, A CORPORATION OF OHIO.

FUEL-GAS-CONTROLLING VALVE

1,162,314.

Specification of Letters Patent. Patented Nov. 30, 1915.

Application filed January 11, 1913. Serial No. 741,414.

To all whom it may concern:

Be it known that we, HARRISON H. SOUTHWORTH and GEORGE A. GASE, citizens of the United States, and residents of Cleveland, 5 in the county of Cuyahoga and State of Ohio, have invented certain new and useful Improvements in Fuel-Gas-Controlling Valves; and we do hereby declare that the following is a full, clear, and exact description thereof, reference being had to the accompanying drawings, and to the letters of reference marked thereon, which form a 10 part of this specification.

This invention relates to a fuel gas controlling valve more especially adapted for use in connection with the fuel gas supply of an absorption refrigerating apparatus and consists of the matters hereinafter described and more particularly pointed out 20 in the appended claims.

The invention is shown as applied to an absorption refrigerating apparatus of the type described in an application heretofore filed by Harrison H. Southworth and Fred 25 W. Wolf, Serial No. 727,353, filed on the 23rd day of October, 1912, but may be applied to other apparatus requiring the use of a like controlling valve.

In the drawings:—Figure 1 is a view representing a front elevation of a refrigerating apparatus of the type described provided with our improved fuel controlling valve. Fig. 2 is a view representing a partial vertical section taken in a plane immediately back of the front wall of the case 30 inclosing the apparatus, as shown in Fig. 1, with the parts in one position. Fig. 3 is a like view showing the parts in another position. Fig. 4 is a view representing a vertical section through Fig. 2 in a plane indicated by the line 4—4 thereof. Fig. 5 is a view representing a vertical central section through the controlling valve mechanism.

The refrigerating apparatus to which our improved fuel controlling valve is shown as applied, is of the alternating absorption type and includes two generator-absorbers 10, 11, which act in alternate cycles as generators and as absorbers, the one during one cycle 45 being heated while the other is being cooled and vice versa. Said drums are supported within a casing 12 above a large cooling wa-

ter tank 13 which contains a liquid condensing and receiving coil 14, and into which the cooling water flows after it has been applied to that one of the drums which is being cooled.

15 indicates a burner which is adapted to be shifted from burning position under one drum to burning position under the other 60 drum, its two positions being indicated, respectively, in Figs. 2 and 3. In the apparatus herein shown, the motive power for shifting the burner is supplied by the cooling water falling from the drum which is being cooled, which cooling water falls into that one of two troughs 16, 17 (fixed at the sides of and movable with the burner) which stands under the drum which is being cooled, and catching the water, acts by reason of the 65 weight of the water to shift the burner when the burner is released, as described in the application hereinbefore referred to.

Cooling water is supplied to cool the generator-absorber drums through a nozzle 18 75 which is capable of a shifting movement to direct the cooling water into one or the other of two compartments 19, 20 in a tank 21, said compartments being connected, respectively, with pipes 19^a, 20^a, located above the 80 respective drums and adapted to discharge cooling water thereon when the nozzle 18 is in position to discharge water into the associated compartment of the trough. The construction thus far described will be readily 85 understood and, as it forms no part of the present invention, a further description thereof will be unnecessary.

22 indicates a fuel gas supply pipe and 23 a casing containing a float chamber into 90 which said pipe opens. Said casing, as shown, has a cylindric side wall 23^a, a top wall 24, and a bottom wall 25.

A valve-seat 26 is provided at the point of communication between the fuel supply 95 pipe 22 and the casing 23, and 27 indicates a valve adapted to co-act with said seat to control the flow from said fuel gas supply pipe to the casing 23. 28 indicates a stem made rigid with said valve and depending 100 down through the casing and through its bottom wall 25.

29 is a float of any suitable construction rigidly fixed on the stem 28 and having

loose bearing engagement with the side wall 23^a of the casing.

Arranged adjacent to the casing 23 is a short stand-pipe 30 the lower end of which is connected by means of a suitable casting 31 with the casing 23 which casting contains a passage 31^a connecting the stand-pipe with the interior of the casing 23 at its bottom.

32 indicates a horizontal pan secured to the upper end of the stand-pipe 30 and extending transversely of the apparatus so as to receive any water that drips from either of the troughs 16 and 17, through notches 16^a; 17^a, provided at the front ends of said troughs. As shown, spouts 16^b, 17^b, are provided at said notches to direct the water into said pan 32.

To the bottom of the casting 31, that extends between the bottom of the casing and the bottom of the pipe 30, is pivoted a lever 33. One end of said lever is extended into a position in line with the valve stem 28 which projects through an aperture in said lever and which is provided with a nut 34 for engagement with the lower side of said lever. The other end of said lever 33 is connected by a vertical link 35 to a second lever 36 located in the neighborhood of the front end of the burner and being fulcrumed at one end 37 to the front wall of the casing surrounding the refrigerating apparatus. Its other end 38 is connected by a coiled spring 39 to an arm 40 rigidly secured to said casing wall. The said spring normally tends to hold the lever 36 in its highest position and it in turn acts, as will be readily apparent, to hold the valve stem 28 in its lowest position, in other words, acts to hold the valve 27 closed against its seat. The burner is provided with an arcuate arm 41 having lugs 41^a, 41^b, which project into the plane of the lever 36 and the parts are so arranged that when said burner is in heating position under either of the generator-absorber drums, said lugs will act to depress the lever 36 so as to allow the valve 27 to rise from its seat; while if the burner is at any intermediate position, the spring 39 will lift the lever 36 and thus close the valve upon its seat.

The top wall 24 of the casing 23 is provided with a passage 42 which is connected with a nozzle 43 arranged to direct the flow of gas into the inlet end of the burner 15, in a familiar manner.

The operation of my improved fuel controlling valve mechanism is as follows: When the valve 27 is raised from its seat, the fuel gas passing through the supply pipe 22 into the float-chamber 23 passes by way of the passage 42 and the nozzle 43 into the burner. The pressure of the gas in the float chamber will tend to depress the water and thus force the water out of the bottom of the casing 23 up into the pipe 30. The float

of course follows the water level. Thus under a certain pressure of gas, the float 29 will stand at a certain level in the casing 23, the difference in the level of the water in the casing 23 and of the level of the water in the pan 32 at the top of the pipe 30 being in proportion to the head of gas. The parts are so constructed and arranged that with this normal pressure the burner will get enough gas to maintain the desired flame, there being a certain valve opening under these conditions. Should the pressure of the gas from the supply pipe for any reason increase, as when gas jets in other parts of the building are turned off, the increased pressure will act to depress the water level and with it the float in the casing 23 which will cause the water in the float chamber to flow into the pipe 30 and up into the pan 32, which will overflow. The depressing of the float 29 will produce a partial closing movement of the valve 27 thus acting to cut down or choke the gas coming through into the float chamber 23 so as to maintain the pressure in the float chamber and also at the burner at substantially the initial pressure. A reduction of the gas pressure in the supply pipe will have the opposite effect, first acting to reduce the pressure in the chamber 23 and permit the water and the float to rise in said chamber. This produces an opening movement of the valve so that more gas may flow into the float chamber. Thus the action of the device is to maintain a constant pressure in the chamber 23 and therefore a constant pressure of gas at the burner. The adjustment of the float on the valve stem provides for the initial adjustment of the parts to produce the required valve opening for the predetermined gas pressure. As before pointed out when the burner moves to an intermediate position the valve is closed by the levers 36 and 33, thus cutting off the supply of gas entirely and putting out the burner.

A small opening 25^a is provided in the bottom wall of the casing 23 so that in case the water supply should for any reason be cut off entirely, the water in the pan 32, stand-pipe 30, and at the bottom of the float-chamber 23, will flow out through this opening, and the float 29 will fall of its own weight and close the valve 27 on its seat, thus entirely cutting off the supply of gas.

A pilot burner 50 is connected to the fuel gas supply pipe above the valve 27 and is attached to the burner so as to swing therewith and always be in position to light the burner when the gas is turned on.

We claim as our invention:—

1. The combination, with a burner and a pipe for supplying fuel gas thereto, of a valve for controlling the supply of gas through said pipe, means for operating said valve adapted to be acted upon in one direction by a column of liquid and acted upon 125

in the other direction by the gas pressure, there being a comparatively small constantly open draining vent from the liquid column, whereby a failure of liquid supply causes 5 the closing of the gas valve.

2. The combination, with a burner and a supply conduit thereto for fuel gas, of a valve in said conduit, and a column of liquid having a constant head adapted by its head 10 to hold the valve open, there being a comparatively small constantly open draining vent from the liquid column, whereby a fail-

ure of liquid supply causes the closing of the gas valve.

In testimony, that we claim the foregoing 15 as our invention we affix our signatures in the presence of two witnesses, this eighth day of January A. D. 1913.

HARRISON H. SOUTHWORTH.
GEORGE A. GASE.
